PULLEY HANGER BRACKET FOR DRAW CURTAIN FIXTURES

Filed Nov. 27, 1925

Inventor
James H. Boye,
By Samuel N. Pond, Atty.

UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

PULLEY-HANGER BRACKET FOR DRAW-CURTAIN FIXTURES.

Application filed November 27, 1925. Serial No. 71,522.

To all whom it may concern:

Be it known that I, JAMES H. BOYE, a citizen of the United States, residing at Chicago, in the county of Cook and State 5 of Illinois, have invented certain new and useful Improvements in Pulley-Hanger Brackets for Draw-Curtain Fixtures, of which the following is a specification.

This invention relates to curtain fixtures 10 of the draw curtain type, and has reference more particularly to an improved hanger bracket for suspending from the curtain rod the pulleys over which the draw cord is trained.

15 In an earlier application filed by me on the 17th day of January, 1925, Serial No. 2,977 I have disclosed a draw curtain fixture equipped with pulley hanger brackets mounted on the end portions of the rod 20 which are suspended from the latter by a hook at the upper end of the bracket and are locked against swinging forwardly of the rod by integral tongues cut and pressed up behind the lower edge of the rod. These 25 brackets are locked against sliding movement lengthwise of the rod by set screws passed through the front portions of the brackets and bearing against the front face of the rod.

30 One object of my present invention is to provide an improved hanger bracket of this general type that will not require the use of any tool to mount it on the rod but may be readily snapped in place on the latter by 35 the pressure of the hand. Another object is to provide a bracket of this type that will not require binding screws or similar devices to lock it against shifting lengthwise of the rod. Still other objects and advantages of the invention will be apparent to 40 persons skilled in the art as the same becomes better understood by reference to the following detailed description, taken in connection with the accompanying drawing in 45 which I have illustrated one practical and approved embodiment of the invention, and wherein—

50 Fig. 1 is a front elevation of a draw curtain fixture of the flat curtain rod type showing the upper edge portions of the curtains suspended therefrom and my improved pulley hanger brackets applied thereto;

Fig. 2 is an inner edge elevation of the

right hand bracket shown in Fig. 1, with the rod in section;

Fig. 3 is a rear elevation of the hanger bracket; and

Fig. 4 is a vertical section on the line 4—4 of Fig. 3.

Referring to the drawing, 10 and 11 60 designate respectively the inner and outer telescoping sections of a curtain rod of the well known flat type, and 12 designates brackets in which the elbow shaped ends of 65 the rod sections 10 and 11 are mounted and supported. 13 designates each of the two halves of the curtain, which are suspended at their upper edges from the curtain rod by hangers 14, the structural features of 70 which constitute in part the subject-matter of my aforesaid application, and are immaterial to the present invention.

The curtains are simultaneously drawn together and simultaneously drawn apart by 75 means of the customary draw cord that is trained over guide pulleys suspended by brackets mounted on the end portions of the curtain rod, in a manner well understood in the art. The two depending limbs 80 of the draw cord at one end of the rod are trained over a pair of horizontally journaled pulleys, while the folded or looped end of the cord is trained around a vertically journaled pulley carried by the hanger 85 bracket at the opposite end of the rod. My present invention is concerned only with novel structural features of these pulley hanger brackets.

Referring more particularly to Figs. 2, 90 3 and 4, 15 designates a relatively long narrow flat strip of metal formed on its upper end with a rearwardly turned hook 16 that engages over and substantially fits the upper rounded or beaded edge of the 95 rod. Integral with the lower portion of one edge of the strip 15 is a rearwardly projecting arm 17, the forward portion 18 of which is bent at right angles into a plane parallel with the plane of the strip 15, the parts 15 and 18 supporting a pintle 19 on which are journaled a pair of pulleys 20, 21. Attached to the lower portion of the strip 15 as by a rivet 22 is the stem or shank 23 of a spring tongue 24 that projects rearwardly through a substantially central hole 25 in the strip 15, and lies beneath the free edge of the hook 16. Also projecting rear-

wardly from and integral with the opposite edges of the strip 15 are a pair of lugs 26 formed with substantially flat upper edges adapted, when the bracket is hung on the 5 rod, to bear against the lower edge of the latter on opposite sides of the spring tongue 24.

The foregoing description applies to the 10 right hand hanger bracket shown in Fig. 1; it being understood that the left hand bracket is identical except that it carries a single vertically journaled pulley at its lower end.

To mount the bracket on the rod it is 15 necessary only to first engage the hook with the upper edge of the rod and then lightly press the bracket toward the rod until the tongue 24 slides past and snaps up behind the lower edge of the rod. This 20 yieldably locks the bracket against swinging outwardly from the rod, while, at the same time, permitting it to be easily removed by pulling outward on the lower end of the bracket to disengage the tongue 24.

25 Binding screws to prevent sliding movement of the bracket on the rod under the pull of the cord are wholly unnecessary, since the pull of the cord tends to cant the bracket edgewise, and this is resisted by the 30 lugs 26 which, under such canting pull bind with ample friction against the lower edge of the rod to prevent displacement of the bracket on the latter; the lug on the inner edge of the bracket being principally effective for this purpose. In this action the 35 tongue also co-operates, and manifestly, if the tongue is made of sufficient width, the lugs 26 may be dispensed with.

40 While I have shown and described one practical embodiment of the invention which in practice has been found to satisfactorily effectuate the stated purposes and objects thereof, it is manifest that minor variations in structural details may be resorted to without departing from the substance of the invention or sacrificing any of the advantages thereof. Hence I reserve all such variations and modifications as fall 45 within the spirit and purview of the appended claims.

50 I claim—

1. A pulley hanger bracket for draw cur-

tain fixtures, comprising a metal strip formed at its upper end with a hook to engage over the upper edge of a curtain 55 rod and at its lower end with a pulley bearing and pulley, and a spring attached to said strip with a free portion thereof projecting rearwardly of the latter and adapted to snap beneath and behind the lower edge 60 of the rod.

2. The combination with a flat curtain rod, of a pulley hanger bracket comprising a flat metal strip transversely overlying the front of said rod and formed at its upper 65 end with a suspension hook engaged with the upper edge of the rod and at its lower end with a pulley bearing and pulley, said strip also formed with a hole therethrough below the lower edge of the rod, and a spring attached to the front face of said strip and having a tongue projecting through said hole adapted to snap beneath and behind the lower edge of the rod to yieldably lock the strip to the latter. 70

75 3. A pulley hanger bracket for draw curtain fixtures, comprising a metal strip formed at its upper end with a hook to engage over the upper edge of a curtain rod, at its lower end with a pulley bearing 80 and pulley, and on an edge thereof with a rearwardly extending lug adapted to engage with the lower edge of the rod, and a spring attached to said strip and formed with a tongue projecting rearwardly of the latter 85 and adapted to snap beneath and behind the lower edge of the rod.

90 4. The combination with a flat curtain rod, of a pulley hanger bracket comprising a flat metal strip transversely overlying the front of said rod and formed at its upper end with a suspension hook engaged with the upper edge of the rod, at its lower end with a pulley bearing and pulley, and on 95 its edges with rearwardly extending lugs adapted to engage with the lower edge of the rod, said strip also formed with a hole therethrough below the lower edge of the rod, and a spring attached to the front face of said strip and having a tongue projecting through said hole adapted to snap beneath and behind the lower edge of the rod to yieldably lock the strip to the latter. 100

JAMES H. BOYE.
